United States Patent Office

Des. 196,217
Patented Sept. 3, 1963

196,217

FIREPLACE STOVE

Harry L. Yager, 030 SW. Ridge Drive, Portland, Oreg.

Filed Aug. 7, 1961, Ser. No. 66,213

Term of patent 14 years

(Cl. D81—7)

FIG. 1 is a perspective view illustrating the front and one side of the fireplace stove showing my new design;

FIG. 2 is a front elevation thereof;

FIG. 3 is an elevation of the side opposite that shown in FIG. 1;

FIG. 4 is a rear elevation of the fireplace stove; and

FIG. 5 is a top plan view thereof.

I claim:

The ornamental design for a fireplace stove, as shown.
